UNITED STATES PATENT OFFICE.

JOHN F. ISBELL, OF ALHAMBRA, CALIFORNIA; CLEMENTINE ISBELL, ADMINISTRATRIX OF SAID JOHN F. ISBELL, DECEASED, ASSIGNOR OF ONE-HALF TO OTTO Q. BECKWITH, OF LOS ANGELES, CALIFORNIA.

SCREEN SEPARATOR.

Application filed March 9, 1923. Serial No. 623,929.

To all whom it may concern:

Be it known that I, JOHN F. ISBELL, a citizen of the United States, and a resident of the city of Alhambra, county of Los Angeles, and State of California, have invented new and useful Improvements in Screen Separators, of which the following is a specification.

In the present invention—hereinafter designated in its preferred specific embodiment—I have devised and perfected a screen separator, of the type commonly termed in the art "grizzlies" or "chain grizzlies," for separating and sizing ores, crushed rock, gravel and similar materials.

I have embodied in my invention certain principles of structure, the foremost object of which is to obviate possibility of the screen becoming clogged by fragments wedging in the interstices; and, by eliminating clogging, or reducing it to a minimum, I accomplish the screening of the materials in a more rapid, efficient and economical manner.

My structural principle may be embodied in either rotary or flat screens; may be used with equally good success for either wet or dry screening; and is adaptable to either light or heavy structures for handling materials ranging in size from comparatively fine to very heavy and coarse.

The salient features of my invention will be more fully set forth in the following detailed disclosure, which is to be taken in connection with the accompanying drawings, illustrating the preferred form of construction, and in which:

Fig. 1 is a side elevation illustrating the arrangement of the principles of my invention in a revolving screen;

Fig. 2 is an elevation of the feed end of the device illustrated in Fig. 1;

Fig. 3 is an elevation of the discharge and driving end of the device, illustrated in Fig. 1;

Fig. 4 is a transverse section, on a slightly enlarged scale, taken as indicated by the line 4—4 of Fig. 1;

Fig. 5 is a fragmentary top plan view of my improved screen;

Fig. 6 is a transverse vertical section taken through the screen as indicated by the line 6—6 on Fig. 5;

Fig. 7 is a fragmentary perspective view

of my screen constructed as illustrated in Figs. 5 and 6;

Fig. 8 is a fragmentary plan view of a slightly different form of construction of my screen; and

Fig. 9 is a side elevation of the arrangement shown in Fig. 8, being taken as indicated by the line 9—9 of that figure.

In perfecting this invention I have had in mind two desirable features which I have incorporated in my screen, these being—
(1) the construction of a screen wherein possibility of clogging, resulting from fragments of the material being screened lodging or wedging in the interstices, is obviated or reduced to a minimum; and, (2) one which will be sufficiently durable in structure to handle all classes of materials, principally heavy materials, and which will withstand the severe wear and strain imposed upon screens of this type in the handling of the heavier materials. While the following detailed disclosure will be directed to an exposition of the preferred specific form of my invention, it is, nevertheless, to be understood that I reserve the right to make such changes or modifications in structure and arrangement as will properly come within the scope of the appended claims.

In Figs. 1 to 4, inclusive, I have illustrated the manner in which my structural principles may be embodied in a revolving screen; while in Figs. 5 to 9, inclusive, I have illustrated the manner in which the same principles and arrangement of structure may be embodied in a flat screen. In the former the material is caused to gravitate over the screen surface by its rotation, while in the latter its mobility may be induced either by jets of water or by longitudinal reciprocal agitation.

Referring first to Figs. 1 to 4, inclusive, the numeral 10 designates a frame or base upon which the screen mechanism—generally designated by the numeral 11—is rotatably mounted. The screen 11 is revolvably mounted upon the frame 10 by means of two end rings 12 and 13, rigidly connected together in axial alinement by means of angle irons 14, upon which latter members the screen element 15 is rigidly mounted.

The ring 12, forming the feed end of the screen, consists of a pair of coaxial flanges 16 and 17, reenforced by a peripheral flange

18. The flange 17 forms a bearing ring, for supporting this end of the screen, which (ring) is supported upon a pair of rollers or trunnions 19; the latter being mounted 5 to freely rotate in bearings 20 on the frame 10. The ring 13 is preferably formed of a flat plate or disk 21 having an annular flange 22, disposed in axial alinement with the flange 17 of the ring 12. The plate portion 21 carries a spindle 23 preferably formed integral therewith, which is revolvably journaled in a suitable bearing 24, also supported upon the frame 10. A ring gear 25 is rigidly secured to the plate 21, 10 concentric with the spindle 23, and is adapted to be engaged by an intermeshing pinion 26 rigidly mounted upon a drive shaft 27; the latter being revolvably journaled in a suitable bearing 28 also supported upon the frame 10. Thus rotation 15 of the shaft 27, will, through the medium of the pinion 26 and ring gear 28, effect rotation of the screen 11 in the direction indicated by the arrows in the several figures. 20 25 The angle irons 14, which rigidly connect the rings 12 and 13 and support the screen 15, are connected to the latter by seating in angularly notched brackets 29 and 30, respectively, and to which the members 14 are 30 rigidly secured, as by means of suitable bolts. Preferably the members 14 will be mounted, relative to the rings 12 and 13, in the manner illustrated in Fig. 4.

35 An imperforate metallic sleeve 31 may be secured to the flange 17, of the ring 12, to extend inwardly concentric therewith; and through which the material to be screened may be fed to the screen 15. The sleeve 31 also affords a means for washing the material before it is discharged onto the screen 15, to facilitate in its separation. As the materials to be separated pass over the screen 15, the fines will be separated and fall through the interstices and be discharged through the bottom thereof, while the tailings or oversized materials will be discharged from the screen 15 intermediate its end and the ring 13, as indicated by arrows in Fig. 1.

50 In Fig. 4 I have illustrated the manner in which the principles of my invention are embodied in this type of revolving screen. In the first instance it will be preferably made in the form of individual rings 32, 55 (either by casting or drop forging) having angular notches 33 in their peripheries, reinforced by lateral flanges 34, which engage the members 14 for rigidly holding them in place. It may be here noted that any number of the members 14 may be used, depending upon the rigidity of the construction desired and the character of material the screen is designed to handle, but for all practical purposes four of the members 14 will be ample when disposed in the manner

illustrated. This offers the least possible obstruction to the discharge of the fines through the screen.

Each of the rings 32 comprises a substantially flat body portion 35, extending in a plane substantially at right angles to its axis and in which the notches 33 are formed. Bores 36 are disposed at suitable intervals around the rings 35, and, preferably, these bores will be surrounded by bosses 37, to 75 extend beyond the opposite faces of the body portion 35, to act as spacers for the latter when they are mounted upon the members 14, as illustrated in Fig. 1. When so mounted the rings will be rigidly held in 80 juxtaposition by rods 38 extending through the bores 36 throughout the length of the screen.

The rings 32, being first formed as individual flat rings, are, when mounted upon the members 14, radially cut and their severed ends sprung over and welded to the opposed similarly severed ends of the adjacent rings; so that when completed the screen 15 will be in the form of a continuous spiral. This spiral construction will 90 conduce to movement of the tailings from the feed end to the discharge end of the screen when in operation without any appreciable inclination of the latter.

95 A salient feature of my invention is the formation of a screen having a material supporting surface composed of a plurality of steps extending transversely of the direction in which the material passes over it. The treads of these steps, or the surfaces upon which the material to be screened is supported, are composed of a plurality of substantially parallel members having longitudinally tapered ribs upon their top edges; 100 the latter to form tapered interstices therebetween, with the large ends of these interstices disposed towards the discharged end of the screen.

105 In the form illustrated in Fig. 4 the rings 35 form what will be hereinafter termed the "body portion", having its inner edge notched or serrated so that when the rings 35 are joined together in juxtaposition, as illustrated in Fig. 1, these serrated inner edges will form a plurality of steps extending throughout the length of the screen. The material supporting surfaces of the step treads are formed by ribs 39, preferably integral with the rings 35; these ribs being 110 longitudinally tapered so that when the rings are joined together there will be tapered interstices between them. The ribs are so formed, relative to the rings, that when the latter are juxtaposed in operative relation their smaller tapered ends will be at the discharge edges of the steps, so the larger ends of the tapered interstices will also be at such discharged edges of the steps. The ribs 39 will preferably be cylindrical, 115 120 125 130

and greater in width than the width of the body portion 35; however, in some cases it may only be necessary to make them semi-cylindrical, or they may have their top faces 5 rounded, without departing from the principle of my invention. In any event, it is essential that the ribs be wider than the body or supporting portions so that after the fines, as will be more fully later explained, 10 pass between them their further discharge passage will be free and unobstructed.

In the operation of the revolving screen it will be rotated in the direction indicated 15 by the arrow "A" in Fig. 4, which will effect the gravitation of the materials over the screening surface, as indicated by the smaller arrows "B" in that figure.

In Figs. 8 and 9, I have illustrated the 20 flat screen embodying the same structural principles as shown in the construction of the revolving screen illustrated in Fig. 4. In this case the principle is identical, except that the screen may be composed of a plurality 25 of elongated body members 35^a, each having a stepped material supporting surface composed of tapered ribs 39^a formed on its top serrated edge. Transversely disposed apertures 36^a are also provided in the 30 members 35^a, in spaced relation, around which spacing bosses 37^a are formed. Rods 38^a also extend through the apertures 36^a for holding the members 35^a rigidly in juxtaposed relation. A flat screen, constructed 35 as illustrated in Figs. 8 and 9, when in actual use will ordinarily be inclined so that the axes of the ribs 39^a will extend substantially parallel to the horizontal.

The lengths of the members 35^a and the 40 size and spacing of the ribs 39^a will be varied to suit conditions, which will ordinarily be determined by the character of the material the screen is designed to handle. Fig. 8 clearly illustrates the relative positions 45 of the members 35^a and the ribs 39^a, which form the steps; the arrows in that figure indicating the direction in which the material passes thereover. It can there be seen how the tapered ribs 39^a, having their 50 smaller ends disposed toward the discharge end of the screen, form tapered interstices therebetween. It may be here noted that the lengths of the ribs 39^a forming the steps, may also be varied to suit conditions, as 55 may also these portions of the serrated edges which form the step risers.

In Figs. 5, 6, and 7, I have illustrated a 60 slightly different form of construction, in which the screen is composed of a plurality of links, generally designated by the numeral 40. The lengths and size of these links may be varied to suit circumstances, as above described, in connection with the members 35^a. Each of the links 40 is composed of a 65 substantially flat body portion 35^b having

an upper inclined edge 41 upon which a substantially cylindrical tapered rib 39^b is secured; the latter preferably being formed integral with the body portion 35^b. The upward inclination of the upper edge 41, 70 which carries the rib 39^b, is toward the discharge end of the link; the rib 39^b terminating at a slightly outwardly inclined shoulder 43. At the upper, or what might be termed 75 the feed end of the link, a substantially cylindrical bearing portion 44 is formed with its axis extending at right angles to the axis of the body portion 35^b and rib 39^b, in which there is an axial bore 45. The width of the bearing portion 44 is preferably substantially twice that of the body portion 35^b; and the width of the large end of the rib 39^b, where it joins the bearing 80 44, is substantially the same as the latter. The opposite or discharge end of the link terminates in a portion 46 extending slightly beyond the shoulder 43 and through which there is a transverse bore 47 axially parallel with the bore 45. In height the portion 46 is the same as the diameter of the bearing 85 portion 44, and is rounded at its end, as at 48, to conform to the cylindrical configuration of the bearing portion 44, and is clearly illustrated in Fig. 7. The length of the portion 46 beyond the shoulder 43 may be varied 90 to suit circumstances, but under ordinary conditions it will be of such length that when the materials are discharged from the ribs 39^b they will normally drop onto the bearing portions 44, forming the next lower 95 step, or onto the enlarged ends of the ribs 100 39^b.

When formed into a screen the links 40 present the appearance illustrated in Figs. 105 5, 6, and 7. They are joined in longitudinally offset relation with the links forming the next upper and lower steps, with the bearing portions 44 of the links forming one step in transverse alignment with the 110 ends 46 of the links forming the next step above and with the bores 45 and 47 of each in axial registration. Securing rods 49 are then extended through the registering bores 45 and 47 for rigidly holding the links in 115 this juxtaposed relation. The screen thus formed may be mounted in any suitable form of frame and tilted or positioned to suit the handling of the various materials.

It is to be noted that the principal feature 120 of my invention resides in providing a screen having a stepped material supporting surface which will obviate possibility of being clogged by the materials wedging in the interstices as they pass over it. This is accomplished by first forming the material supporting surface of a plurality of longitudinally tapered ribs with their smaller ends disposed in the direction of the discharge edge of the screen. These ribs are preferably rounded or made substantially cylind-

drical to reduce frictional resistance and facilitate in the rapid movement of the material thereover during the screening operation. However, it is not absolutely essential 5 to the success of my screen that these ribs be rounded at all, and where they are rounded it is not necessary that they be substantially cylindrical, as the rounding off of their top edges in a semicylindrical form 10 will accomplish the same results. But in the preferred form of my device I find the structure herein illustrated and described gives extremely satisfactory results. It is very essential that the ribs be tapered smaller 15 toward their discharge ends in order to form the tapered interstices with their larger ends disposed in the direction of the discharge edge of the screen. Another feature of my invention is the disposition of the 20 ribs in such a manner that the materials discharged therefrom on each step will fall onto the enlarged ends of the ribs forming the next step below, which prevents the materials becoming wedged in the enlarged 25 ends of the interstices.

In the operation of the screen the materials are fed to the upper end, or in the case of the cylindrical screen hereinbefore described, at a feed end, and as they travel 30 over the steps which form the material supporting surface of the screen, moving from the larger to the smaller ends of the ribs the fines or undersized materials will pass between the ribs and be discharged between 35 the body portions which support the ribs. In this connection it is to be noted that with my particular structure the body portions form a rigid and unyielding support for the ribs which holds them in absolutely fixed 40 parallel alinement, and that after the fines have passed between the ribs the reduced body portions do not in any way interfere with their subsequent discharge. In other words the substantially flat body portions 45 rigidly support the ribs, but do not interfere with the discharge of the fines. The tapering of the ribs 39 being smaller toward their discharge ends eliminates possibility of the materials binding in the interstices and conduces to continuous mobility of the materials thereover and their rapid and efficient 50 separation.

As I have hereinbefore stated I reserve 55 the right to make such changes or modifications in structure of my screen as will properly come within the scope of the appended claims. A number of such modifications may be resorted to as, for instance, the forming of the screen from a single sheet of 60 metal, in which it is expanded to form the step material supporting surface having interstices therein tapered larger toward the discharge edges of the steps and which may also be formed to present the equivalent

of the rounded ribs 39 hereinbefore described. It may even be practicable to construct my screen of the tapered ribs 39 without the use of the supporting body portions 35, as these are supplied for the purpose of giving great strength and rigidity to the 70 screen thereby conducing it to its long life and adaptability of screening very heavy materials.

Having described my invention, I claim:

1. A rotary screen comprising a substantially tubular screen portion, means for rotatably mounting said tubular member, said member being composed of a plurality of spaced rings having serrated inner edges forming stepped material supporting surfaces extending longitudinally of the tube, and tapered ribs on said edges forming tapered interstices therebetween. 75

2. A rotary screen comprising a substantially tubular screen portion, means for rotatably mounting said tubular member, said member being composed of a plurality of spaced rings having serrated inner edges forming stepped material supporting surfaces extending longitudinally of the tube, and tapered ribs on said edges forming tapered interstices therebetween, said ribs being tapered smaller and the interstices larger towards the discharge edges of the 90 steps. 95

3. A rotary screen comprising a substantially tubular screen portion, means for rotatably mounting said tubular member, said member being composed of a plurality of spaced rings having serrated inner edges forming stepped material supporting surfaces extending longitudinally of the tube, each of said rings being joined to the next adjacent rings to form a continuous helix 100 from end to end and tapered ribs on said stepped edges forming tapered interstices therebetween. 105

4. A rotary screen comprising a base, spaced end rings rotatably mounted on said base in substantially co-axial relation, axially disposed brace members connecting said end rings, a substantially tubular screen portion supported between said end rings on said brace members, said screen portion being formed of a plurality of axially spaced rings in the form of a continuous helix, having serrated inner edges forming stepped material supporting surfaces extending longitudinally of the tube, and tapered ribs on said stepped edges forming tapered interstices therebetween, said ribs being tapered smaller and the interstices larger towards the discharge edges of the 115 steps. 120

In witness that I claim the foregoing I have hereunto subscribed my name this 26th day of January, 1923.

JOHN F. ISBELL.

Certificate of Correction.

It is hereby certified that the name of the assignee in Letters Patent No. 1,576,430, granted March 9, 1926, upon the application of John F. Isbell, of Alhambra, California, for an improvement in "Screen Separators," was erroneously written and printed as "Otto Q. Beckwith," whereas said name should have been written and printed as *Otto Q. Beckworth*, as shown by the records of assignments in this office; and that the said Letters Patent should be read with this correction therein that the same may conform to the record of the case in the Patent Office.

Signed and sealed this 13th day of April, A. D. 1926.

[SEAL.]

M. J. MOORE,
Acting Commissioner of Patents.
